UNITED STATES PATENT OFFICE.

HENRY JAMES COLLIS, OF TAUNTON, MASSACHUSETTS.

ANKLE SUPPORT AND PROTECTOR.

1,084,197.

Specification of Letters Patent.

Patented Jan. 13, 1914.

Application filed May 4, 1912. Serial No. 695,212.

To all whom it may concern:

Be it known that I, HENRY JAMES COLLIS, a citizen of the United States, and resident of Taunton, in the county of Bristol and 5 State of Massachusetts, have invented certain new and useful Improvements in Ankle Supports and Protectors, of which the following is a specification.

This invention relates to devices for supporting and protecting ankles, and it has special relation to devices of this class which are designed for use in athletic sports and which are generally employed in position over the stocking and within the shoe.

15 My present invention embodies certain improvements in the construction of ankle supports and protectors of the type shown in my Patent No. 913,263, granted February 23, 1909, substantially as hereinafter set 20 forth.

The object of my present improvements is to provide a simple device of this class which can be more readily and economically manufactured, which will be extremely simple in 25 construction, which will more effectively avoid chafing and the presence of seams at those points where the extra thickness of seams is undesirable, and which will furthermore possess advantages in point of durability, effectiveness and general efficiency.

In the drawings Figure 1 is a perspective view illustrating the appearance of the device when in use. Fig. 2 is a perspective view with the device open and looking at 35 the inner side. Fig. 3 is a detail side view, showing the seam connection between the upper portion and instep strip. Fig. 4 is a detail cross-section on the line $x-x$, Fig. 2. Fig. 5 is a detail cross-section on the line $y-y$, Fig. 2. Fig. 6 is a plan view of the blank from which the main outside top portion of the device is formed.

Corresponding parts in all the figures are denoted by the same reference characters.

45 Referring to the drawings, 1 designates the main outside portion of the body of the device, which forms the sides, as at 2-2, of the upper portion which surrounds the ankle. The member 1 is constructed in a 50 single piece, from a blank of soft pliable material, such as leather or a suitable fabric, and the blank comprises two corresponding half portions shaped to form the sides 2-2, the front edges of the side portions 2 being 55 curved, as at 4, to form the open front of

the device. The central portion, 6, of the one-piece blank forms the rear portion of the body and is adapted to surround the rear of the ankle above the heel. From another one-piece blank, of suitable shape and likewise of soft pliable material, is formed a strip, 3, which passes under the instep, this instep strip being secured to and carried by the main outside portion 1 of the body of the device. The end edges of the instep strip 65 3 are connected to the lower edges, 5, of the side portions 2 of the main outside upper portion of the body of the device, in any suitable or adapted manner, but I prefer to have the edges of the strip 3 and the edges 70 5 abutting, as herein shown, and secured by a cross stitch, as at 7, thereby forming a continuous smooth surface without overlaps and thus enhancing the comfort and fit of the device in wear, as well as avoiding excess thickness at the side seams above the instep portion, but it will be understood that if desired the edges 5 of the top portion 1 may overlap the edges of the instep strip and be stitched thereto in the form 75 80 of an overlapping seam.

The improved construction as above described thus provides a seamless smooth back section 6, which will effectively avoid any chafing at the back of the ankle above 85 the heel and will provide a soft and pliable condition at this part of the device without excess thickness.

At the inner side of the main portion 1 is provided a body strip, 10, extending over 90 the entire inner face of the upper side portions 2 of the main portion 1 and secured thereto by a suitable stitching, as at 11. This inner body strip is formed of a single seamless blank of soft pliable material, corresponding substantially to both the shape and area of the main outside blank 1, and its central portion therefore covers the inner face of the seamless back section 6 of the main outside body portion of the device. 100 The improved construction and arrangement thus preserves the seamless status of the back section of the device, and avoids any seams or overlaps throughout the rear upper portion of the body of the device 105 which surrounds the ankle, whereby the device is rendered more durable and more effectively resists strains. The seamless upper portion of the body of the device furthermore precludes any possibility of tearing 110

or ripping under strain, both the outer portion 1 and the inner body strip 10 being respectively formed of a single piece of material, and the only connected seams exist 5 at the sides of the device beneath the upper portion which surrounds the ankle and above the lower portion 3 which surrounds the instep.

In the application of my present improvements to the device of the type set forth in my previous patent above mentioned, the general features of construction may be the same as disclosed in that patent. For instance, a series of pockets, as at 14, are 10 formed between the outside main portion 1 strips 15, and having open tops closed by and the inside body strip 10, at the sides 2, said pockets carrying removable stiffening strips, 15, and having open stops closed by 15 an inwardly and downwardly projecting flap, 16, constituted by an extension of the top edge of the main portion 1. Such previous construction also embodies suitable fastening means at the front edges 4, preferably 20 constituted by eyelets, 17, and a lace, 18, and a suitable tongue flap, 19, is carried at the inner side of the device to underlie such fastening means. But in the employment of my improved construction, as herein 25 described, in association with the general structural features just set forth, the series of pockets 14 terminate in front of the smooth and pliable back section 6, whereby the entire back section has a soft and smooth 30 and seamless status, without impairment, and the whole area back of the ankle and above the heel is without seams or excess thickness, it being constituted entirely by a substantially V-shaped portion formed by 35 the central portion of the main outside blank 1 and the central portion of the inner body strip 10. In the improved construction, the top flaps 16 also preferably have their rear ends terminating in front of said 40 soft and seamless approximately V-shaped back portion 6, so that no excess thickness exists at the top thereof, and the top edge of the central portion of the main outside body portion 1 is preferably skived and 45 turned over inwardly, as at 8, and secured by stitching, as at 9, to form a rounded and finished top edge.

The lower edges of the inner body strip 10 terminate above the instep strip 3, 50 and the inner face of the latter is protected by a sweat-proof lining, 20, to protect the single thickness of leather or pliable material at this point. In the constructions as previously employed, the instep 55 portion is liable to rot and break, by reason of its single thickness and position under the instep, where the strongest strain and hardest test in wear is encountered. The sweat-proof lining 20 operates not only to 60 protect the instep strip 3 and prevent rot 65

and breaking or wearing away, but it also reinforces and strengthens the device at this point most subject to strain and wear. The lining 20 is constituted by a strip covering the entire inner surface of the instep portion 3 and secured thereto by a suitable stitching, as at 21, its ends being inserted beneath the lower edge of the inner body strip 10 and likewise secured by a suitable stitching, as at 22. This sweat-proof lining 75 strip may be of any suitable or adapted material having the required water-proof characteristics.

It will be understood that, under some conditions of preferred manufacture, the 80 main body blank 1 and the inner body strip 10 may be cut in pattern to form a closed heel portion like that shown in my above mentioned previous patent, in lieu of the open heel portion, 23, herein illustrated. 85

The operation and advantages of my improvements will be readily understood by those familiar with the athletic arts and the uses for which the device is adapted. The improved construction provides the maximum of comfort, convenience and durability, and produces a soft and pliable status at all tender parts of the foot and ankle, especially at the back section which comes immediately above the heel. The relative 90 construction also secures facility and economy in manufacture and provides for the utilization of the material without waste under the relative pattern conditions which follow from the formation of the upper 100 body portion from two corresponding one-piece blanks and the formation of the instep portion from a single one-piece blank.

Having thus described my invention, I claim and desire to secure by Letters Pat- 105 ent:

An improved ankle support and protector of the class described, comprising a pliable outside main portion forming the side portions of the upper part of the body of the 110 device which extend at each side of the ankle and at the front and at the rear of the ankle above the heel, said outside main portion being seamless at its back section which surrounds the rear of the ankle above the heel, an inner pliable body strip corresponding to and extending over the inner face of said main outside portion and seamless at 115 its rear section which surrounds the rear of the ankle above the heel, said outside main portion and inner body strip being secured together and constituting the main upper portion of the body of the device, and a pliable bottom strip forming the lower portion which extends downwardly from said upper 120 body portion of the device and passes under the instep, the end edges of said separate bottom strip being respectively secured in connection with the respective bottom edges 125 of said main outside portion of the upper 130

body portion of the device, whereby the connecting seams between the separate bottom instep-strip portion and the upper body portion which is constituted by the outside 5 main portion and the inner body strip are at the respective sides of the device immediately beneath the upper body portion and both the outside main portion and the inner body strip of the upper portion of the de-
10 vice present a smooth and seamless surface

at the back section which surrounds the rear of the ankle above the heel.

In testimony whereof I have signed my name in the presence of the subscribing witnesses.

HENRY JAMES COLLIS.
